Primary Examiner — Thomas Johannes*Assistant Examiner* — Catherine Posthauer(74) *Attorney, Agent, or Firm* — Jackson White, PC;
Steven J. Laureanti(57) **CLAIM**

The ornamental design for a cabinet, as shown and described.

DESCRIPTION

FIG. 1 is a perspective view of the present invention; FIG. 2 is a front view of the present invention of FIG. 1; FIG. 3 is a back view of the present invention of FIG. 1; FIG. 4 is a right side view of the present invention of FIG. 1;

FIG. 5 is a left side view of the present invention of FIG. 1; FIG. 6 is a top view of the present invention of FIG. 1; FIG. 7 is a bottom view of the present invention of FIG. 1; and, FIG. 8 is a cross section view taken in the direction of line in FIG. 6.

The evenly broken lines are shown for the purpose of illustrating portions of the article that form no part of the claimed design. The dot-dash boundary lines represent the boundaries of the claim and form no part thereof.

1 Claim, 5 Drawing Sheets(56)
